CONTROL FOR POWER HAMMERS

George R. Murray, Chambersburg, Pa., assignor
to Chambersburg Engineering Company, Cham-
bersburg, Pa., a corporation of Pennsylvania

Application June 17, 1940, Serial No. 341,053

7 Claims. (Cl. 121—30)

This invention relates to a control for fluid-pressure-operated hammers and, more particularly, to a control of that type wherein the movement of the ram is controlled by coacting cam surfaces on the ram and a linkage mechanism connected with the valve supplying and exhausting fluid pressure from the power cylinder.

Such devices as heretofore constructed comprise a linkage carried cam which coacts with an inclined surface formed on the ram. This inclined surface, insofar as its engagement with the cam of the linkage is concerned, has been made substantially continuous; that is to say, there is permanent engagement during any normal operation of the hammer. Through adjustment of the linkage, the operator can set the hammer to remain at any given level above the anvil, but with such prior constructions there is continuous oscillation of the ram by reason of the fact that the cam engagement permits sufficient oscillation of the valve controlling supply and exhaust to intermittently introduce fluid pressure to opposite ends of the cylinder. This operation, obviously, results not only in considerable wear on the working parts, but likewise results in a waste of fluid pressure.

An important object of the present invention is the provision of a construction such that the ram may be brought to fixed rest at any selected point simply by release of the ordinary operating treadle with which the linkage mechanism is supplied, or be made to oscillate as desired.

Another object of the invention is to accomplish this end with but slight modification of the present hammer structure and at a cost no greater than is met with in the production of the present control mechanism.

These and other objects I attain by the construction shown in the accompanying drawings wherein,

Fig. 1 is a diagrammatic view illustrating the hammer provided with a control constructed in accordance with my invention;

Fig. 2 is a plan view of the ram and the associated portions of the control mechanism;

Fig. 3 is a section on line A—A of Fig. 2, the ram being shown in the position of rest; and

Fig. 4 is a view similar to that of Fig. 3, but showing the ram in the position where oscillation will take place.

Referring now more particularly to the drawings, the numeral 10 generally designates the ram of a power hammer; 11, the anvil with which it coacts; 12, a power cylinder the piston 13 of

which is connected to the ram 10 through rod 14; and 15, a valve for controlling the movement of the piston and ram. In the illustration of Fig. 1, the movable valve element 16 is shown as disposed in an intermediate position where no fluid pressure from inlet 17 may reach either of the conduits 18 or 19 leading respectively to the upper and lower ends of cylinder 12. Upon downward movement of this valve, fluid pressure may exhaust from the upper end of cylinder 12 through conduit 18, the hollow center 20 of the movable valve element 16, and the exhaust pipe 21, while fluid pressure will be introduced at the lower end of the cylinder through intake pipe 17 ports, 22 and 23, and conduit 19. Correspondingly, upon elevation of the movable valve element, fluid pressure will be introduced to the upper end of the cylinder and exhaust will take place below the valve element to exhaust 21.

The position of the valve is controlled through a linkage mechanism 24 including a lever 25 operated by a treadle 26 connected to the lever through a link and lever structure including an adjustment at 27 whereby a normal position of valve element 16 in a given elevated position of treadle 26 may be readily determined. The upper position of treadle 26 is limited by a suitable stop 26a against which it is normally held by a spring 26b. This adjustment mechanism, while shown in extremely simple form, may be, and preferably is, of that type shown in the patent to Murray and Clarke, No. 2,218,684, for "Control for power hammers," issued October 22, 1940. Supported by lever 25 is a bell crank mechanism 28 having one arm 29 in the form of a cam engaging a cam surface 29 on ram 10. The other arm of this bell crank lever is linked to valve elements 16 to operate the same, the connections being such that upon depression of pedal 26 the valve element is lifted to admit fluid pressure to the upper end of the cylinder. In the ordinary hammer, when fluid pressure is supplied, the ram tends to oscillate slightly in an elevated position. As treadle 26 is moved downwardly, the ram moves with it, the speed of its movement depending on that of the treadle. If the treadle is only partially released, the ram will follow the treadle upwardly and then oscillate at the point determined by the treadle position. As above pointed out, this oscillation will continue even after the treadle has been completely released.

In accordance with my invention, the cam surface 29 is broken up into two sections, the first of which, indicated at 30, is inclined with respect to the axis of the ram and is arranged uppermost,

the other of which, indicated at 31, is parallel to the axis of the ram. The cam 28 is preferably provided with a flat, or substantially flat, section, indicated at 32 which is adapted to cooperate with the section 31 of the cam 29. When surfaces 32 and 31 of cams 28 and 29 are in engagement with one another, the valve element 16 will be held in its position as illustrated in Fig. 1, and the ram will, accordingly, remain stationary and the position of the ram at this time may be determined through adjustment of the linkage at 27. Upon depression of pedal 26, the cam will come into operative engagement with the section 30 of cam 29, with the immediate result that operation of the hammer will begin. At this time, the hammer will operate after the manner of the usual hammer above described, the hammer following the treadle and oscillating at any point where the treadle may be held if the treadle be only partially released. However, upon complete release of the treadle, the hammer will elevate until the cam surface 31 is coacting with cam 28, at which time the ram will become stationary. The position of the ram at this time may, of course, be regulated through adjustment 27.

It will be obvious that by an arrangement of this character a considerable saving in fluid pressure may be effected, and it will also be obvious that there will be a correspondingly reduced wear and tear upon the elements of the control which are under constant motion as long as the cam 28 is engaged with the working section 30 of cam 29.

It will also be obvious that the construction illustrated is capable of considerable modification without departing from the spirit of my invention and I, accordingly, do not wish to be understood as limiting myself thereto except as hereinafter claimed.

I claim:

1. In a control for fluid-pressure-operated hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is so constructed and arranged that when it is engaged with the cam movement of the ram will cause shifting of said valve and the other of which is so constructed that during its engagement with the cam the valve will remain stationary and in its neutral position, and means to bodily shift said cam longitudinally of the cam surface of the ram.

2. In a control for fluid-pressure-operated hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is so constructed and arranged that when it is engaged with the cam movement of the ram will cause shifting of said valve and the other of which is so constructed that during its engagement with the cam the valve will remain stationary and in its neutral position, means to bodily shift said cam longitudinally of the cam surface of the ram comprising a lever pivoted to swing in a plane substantially radial to the ram axis and supporting said cam, and a two-position operating member connected to the lever to shift the same.

3. In a control for fluid-pressure-operated

hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is so constructed and arranged that when it is engaged with the cam movement of the ram will cause shifting of said valve and the other of which is so constructed that during its engagement with the cam the valve will remain stationary and in its neutral position, means to bodily shift said cam longitudinally of the cam surface of the ram comprising a lever pivoted to swing in a plane substantially radial to the ram axis and supporting said cam, and a two-position operating member connected to the lever to shift the same, the connections between the lever and operating member comprising an adjustable link.

4. In a control for fluid-pressure-operated hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is inclined with relation to the ram axis whereby when it is engaged with the cam movement of the ram will cause shifting of said valve and the other of which is parallel to the ram axis whereby during its engagement with the cam the valve will remain stationary and in its neutral position, and means to bodily shift said cam longitudinally of the cam surface of the ram to selectively engage the cam with either section of the cam surface of the ram.

5. In a control for fluid-pressure-operated hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is inclined with relation to the ram axis whereby when it is engaged with the cam movement of the ram will cause shifting of said valve and the other of which is parallel to the ram axis whereby during its engagement with the cam the valve will remain stationary and in its neutral position, and means to bodily shift said cam longitudinally of the cam surface of the ram to selectively engage the cam with either section of the cam surface of the ram comprising a lever pivoted to swing in a plane substantially radial to the ram axis and supporting said cam, and a two-position operating member connected to the lever to shift the same.

6. In a control for fluid-pressure-operated hammers, a ram, a cylinder to operate the ram, a valve controlling the intake and exhaust of the cylinder and having a neutral position, a cam linked to the valve to operate the same, a coacting cam surface on the ram, said cam surface embodying two sections engageable by the cam one of which is inclined with relation to the ram axis whereby when it is engaged with the cam movement of the ram will cause shifting of said valve and the other of which is parallel to the ram axis whereby during its engagement with the cam the valve will remain stationary and in its neutral position, and means to bodily shift said cam longitudinally of the cam surface of the ram to selectively engage the cam with either section of the cam surface of the ram comprising a lever pivoted to swing in a

plane substantially radial to the ram axis and supporting said cam, and a two-position operating member connected to the lever to shift the same, the connections between the lever and operating member comprising an adjustable link.

7. In a control for fluid-pressure-operated hammers, a ram, a cylinder to operate the ram, a valve controlling the intake and exhaust of the cylinder and having a neutral position, a cam linked to the valve to operate the same, a co-acting cam surface on the ram, said cam surface embodying two sections engageable by the

cam one of which is inclined with relation to the ram axis whereby when it is engaged with the cam movement of the ram will cause shifting of said valve and the other of which is parallel to the ram axis whereby during its engagement with the cam the valve will remain stationary and in its neutral position, and means to bodily shift said cam to selectively engage the cam with either section of the cam surface of the ram.

GEORGE R. MURRAY.
